UNITED STATES PATENT OFFICE.

JOHN H. AUSTIN, OF JERSEY CITY, NEW JERSEY.

ASH-SIFTER.

No. 834,604.

Specification of Letters Patent.

Patented Oct. 30, 1906.

Application filed February 10, 1906. Serial No. 300,403.

To all whom it may concern:

Be it known that I, JOHN H. AUSTIN, a citizen of the United States, residing at Jersey City, in the county of Hudson and State 5 of New Jersey, have invented certain new and useful Improvements in Ash-Sifters, of which the following is a specification, such as will enable those skilled in the art to which it appertains to make and use the same.

This invention relates to sifters for separating ashes from charred coal or small particles of coal which are not consumed; and the object thereof is to provide an improved device of this class which is simple in construction and operation and comparatively inexpensive and by means of which ashes may be sifted from charred coal and other substances without the escape of dust from the sifter.

The invention is fully disclosed in the following specification, of which the accompanying drawings form a part, in which the separate parts of my improvement are designated by suitable reference characters in 25 each of the views, and in which—

Figure 1 is a central longitudinal section of my improved ash-sifter and showing the method of using the same; Fig. 2, a plan view of the sifter, part of the construction 30 being broken away.

In the practice of my invention, as shown in Figs. 1 and 2, I provide an oblong box or casing *a*, the rear end portion of which is open at the bottom, as shown at *a*², and the front top portion of which is provided with an opening *a*³, having a door *a*⁴, hinged at *a*⁵ and adapted to be folded backwardly, so as to lie on the top of the box or casing *a* or to be folded forwardly, so as to close the opening *a*³. Mounted on the front top portion of the casing *a* is a receiver *b*, having a sifter-bottom *b*², composed of wire-cloth, perforated metal, or any other suitable material, and the receiver *b* is provided with a rod *b*³, which passes through the front end wall of the box or casing *a* and is provided with a handle *b*⁴, by which the receiver *b*, which constitutes the sifter proper, may be manipulated.

The bottom *b*² of the receiver *b* is hinged to the front end of said receiver, as shown at *b*⁵, and said receiver is mounted on and movable on longitudinally-arranged supports *c*, which extend the full length of the box or casing *a* and are provided in the front end portion of said box or casing with supplemental longi-

tudinally-arranged members *c*², which are secured thereto and between which and the main supports *c* are vertically-arranged recesses or openings *c*³, which in the form of construction shown are formed in the main supports *c*. The bottom *b*² of the receiver *b* is less in transverse width than the main supports *c* and rests on the supplemental supports *c*² and is also adapted to rest on rollers 60 *d*, secured at the rear ends of the supplemental supports *c*² when the receiver *b* is moved backwardly of the box or casing *a*.

The bottom of the front end portion of the box or casing *a* is also provided with an opening *e*, which is preferably circular in form and around which is preferably secured a depending collar or flange *e*, and arranged within the box or casing *a* rearwardly of the opening *c*³ is a downwardly and forwardly inclined member *f*, which in the form of construction shown is placed between the rear end portions of the supplemental supports *c*².

In the operation of this device the box or casing *a*, or the front end portion thereof, is placed over a barrel or other receptacle *g*, as shown in Fig. 1, which is designed to receive the ashes from the sifter, while the rear end portion thereof is preferably placed over a box or other receptacle *g*², designed to receive the charred coal and other substances. The ashes, cinders, and other material are then dumped into the receiver *b*, the door *a*⁴ is closed, and the receiver *b* is agitated or given a reciprocating motion by moving the same backwardly and forwardly by means of the rod *b*³ and the handle *b*⁴ thereof, and in this operation all the ashes are sifted through the bottom *b*² of the receiver *b* and fall into the barrel or other receptacle *g*, and when this operation is fully completed the receiver *b* is forced backwardly into the position shown in dotted lines in Fig. 1, and the bottom *b*² thereof drops downwardly, as is also shown in dotted lines in Fig. 1, and the charred coal and other substances are dumped into the box or other receptacle *g*², and when this is done the receiver *b* may be pulled back into the position shown in full lines in Fig. 1, and in this operation the bottom *b*² thereof strikes 95 on the rollers *d* and is swung into the closed position and is held in said closed position by the supplemental support *c*².

The object of the vertically-arranged recesses or openings *c*³, formed in the supports of the receiver *b*, is to provide means to prevent the accumulation of ashes on said sup-

ports, the ashes which would otherwise lodge on said supports being discharged downwardly through the recesses or openings c^3 .

There is no necessary connection between the sifter or the box or casing a and the barrel or receptacle g and the box or receptacle g^2 , and any suitable holders or receptacles may be provided for receiving the ashes and charred coal and other similar material.

Having fully described my invention, what I claim as new, and desire to secure by Letters Patent, is—

An ash-sifter comprising an oblong box or casing having an opening in the bottom of the front end portion thereof, an opening in the top of the front end portion thereof, a receiver mounted in the front end portion of the box or casing and forming the sifter proper, said receiver being movable longitudinally of the box or casing over the opening in the bottom of the front end portion there-

of, means for giving said receiver a reciprocating motion and for moving it the length of the box or casing, said receiver being provided with a hinged bottom, and the box or casing being provided with an opening in the bottom of the rear end portion thereof, and means for holding the hinged bottom of the receiver in a closed position except when it is in the rear end of the box or casing in which position the bottom of the receiver drops downwardly, substantially as shown and described.

In testimony that I claim the foregoing as my invention I have signed my name, in presence of the subscribing witnesses, this 9th day of February, 1906.

JOHN H. AUSTIN.
